[57] CLAIM

The ornamental design for a folding table, as shown and described.

DESCRIPTION

FIG. 1 is a right front perspective view of a folding

table, showing my new design, the table being in fully folded position but with the carrying handle in projected location ready to be gripped;

FIG. 2 is a view similar to FIG. 1 but with the table in fully unfolded position and the carrying handle in retracted location;

FIG. 3 is a front elevational view of the table in fully unfolded position, as in FIG. 2;

FIG. 4 is an elevational view of the right-hand end of the table in fully unfolded position, as in FIG. 2, the elevational view of the left-hand end being substantially a mirror image thereof;

FIG. 5 is a view similar to FIG. 4 but with the larger of the table surfaces inclined and the table surfaces elevated;

FIG. 6 is a top plan view of the table in fully unfolded position, as in FIG. 2;

FIG. 7 is a bottom plan view of the table in fully unfolded position, as in FIG. 2;

FIG. 8 is a rear elevational view of the table in fully unfolded position, as in FIG. 2; and,

FIG. 9 is a view similar to FIG. 5 but with the smaller of the table surfaces folded into vertical attitude enabling the table to be placed flush against a vertical wall.

The broken line showing of a wall and floor fragment in FIG. 9 is for illustrative purposes only.
